UNITED STATES PATENT OFFICE.

EDWARD B. OELKER AND FREEMAN C. LUDLOW, OF CINCINNATI, OHIO.

PORTABLE HEATER.

1,160,949.

Specification of Letters Patent. Patented Nov. 16, 1915.

Application filed June 19, 1912. Serial No. 704,546.

To all whom it may concern:

Be it known that we, EDWARD B. OELKER and FREEMAN C. LUDLOW, citizens of the United States, residing at Cincinnati, in the 5 county of Hamilton and State of Ohio, have invented certain new and useful Improvements in Portable Heaters, of which the following is a specification.

Our invention relates to improvements in 10 portable heaters.

One of its objects is to provide a heater which may be moved from place to place without liability of injuring the floor, rugs or articles of furniture.

15 Another object is to provide a heater in which the burners while well supplied with air are protected from drafts and excessive air currents.

Another object is to provide a heater in 20 which the heated air is evenly disseminated into the room, and uniform air currents to and from the heater are insured.

Another object is to provide for a supply of fuel thoroughly mixed with air and supplied to the burners in regular quantity and at uniform pressure.

Our invention further comprises certain details of form, combination and arrangement, all of which will be fully set forth 30 in connection with the accompanying drawings in which:

Figure 1 is an end view of our improved heater. Fig. 2 is a vertical section through the same on line *x x* of Fig. 3. Fig. 3 is a 35 horizontal section through the heater on line *z z* of Fig. 2.

The accompanying drawings illustrate the preferred embodiment of our invention, in which—

40 A A' represent the end plates of the heater.

B represents a cylindrical drum supported by the end plates and open to the air of the room at both ends through said end plates.

45 D represents a sheet metal plate encircling the cylinder B and open at the bottom, said plate D being supported in position by and between said end plates.

Gaseous fuel is supplied through the tube 50 2 controlled by the cock 3, and is mixed with external air in the requisite proportion by means of an adjustable mixer 4. The mixed air and gas passes along the tube 5 supported by the end plates A A', in which tube the air 55 and gas are more thoroughly mixed and are heated by reason of the close proximity of

the burner tubes. Various causes such as uneven gas pressure, irregularity in the heating of the air and gas in tube 5 cause the fuel issuing from tube 5 to fluctuate to a 60 certain extent in quantity or pressure, and we therefore provide an equalizing or regulating receptacle 6 to insure a constant supply and practically uniform pressure of gas at the burner jets, said receptacle being 65 interposed between the exit end of tube 5 and the inlet ends of the burner tubes 7 and 8. This chamber 6 is preferably formed by being cast integral with the end plate A, and provided with inwardly projecting 70 bosses 9, 10 and 11, to receive and support the ends of the tubes 5, 7 and 8. The plate A' is provided with blind or closed bosses 12 to receive and support the opposite ends of the tubes 7 and 8, and a perforated boss 75 14 for the passage of the tube 5.

The burner jets or perforations in the respective tubes 7 and 8 are arranged as indicated in Figs. 2 and 3, so as to cause a circulation of heated air and products of combustion around the drum B and between said drum and the plate D, thereby heating said drum B and plate D and causing the air in contact with the inner face of the drum and the outer face of plate 85 D to become heated and to circulate by the laws of convection, giving place to fresh cooler air from beneath the heater.

In order to control the circulation of air to and from the heater and protect the floor 90 and articles of furniture from being excessively heated or injured, and to protect the burners from excessive drafts or air currents we provide an imperforate plate E beneath the burners which receives heat by 95 radiation downwardly from the burners, and protects the floor or rugs from excessive heat or injury. The heat taken up by the plate E is given off above and below to air currents entering through the openings 15 100 and 16 in the respective end plates A A'. The air currents entering the openings 15 beneath plate E take up heat from said plate and then pass out through openings in the perforated side plates 17, 18, thus 105 maintaining a supply of cool air in contact with the floor or rug beneath plate E. The air entering the openings 16 takes up heat from the upper face of plate E and then either passes out directly through openings 110 in the side plates 17 and 18, or rises and takes up heat from the exterior of plates D

and then passes out through openings in the side plates 17, and 18. A perforated plate or cap H is preferably detachably seated above the upper portion of the plate D and air enters through the lower perforations in the sides of said cap, becomes heated by contact with the exterior of plate D and escapes through perforations in the top and upper portion of the sides of said cap. If desired, the cap H may be removed or omitted. Also if desired, one of the side plates 17 and 18 may be imperforate and the other perforated, thus directing the heated air currents chiefly to one side of the heater.

15 Our improved heater thus protects itself from drafts and air currents, and may be freely and safely moved about without danger of injury from excessive heat, and while in operation, furnishes a copious supply of air heated to moderate degree.

The device herein illustrated and described is capable of considerable modification without departing from the principle of our invention.

20 Having described our invention what we claim is:

1. A portable heater comprising substantially vertical end plates each having upper and lower air inlet ports through their lower 30 portions, a substantially cylindrical heating member supported upon and between the upper portions of said end plates above said air inlet ports and provided with a central air heating drum open at both ends, an imperforate substantially horizontal deflector plate below said heating member and between the upper and lower air inlet ports and between said end plates, and substantially vertical side plates extending from 35 one of said end plates to the other on opposite sides of said heating member, and inclosing the space below said heating member to the floor, one of said side plates being perforated, and said several plates being so arranged as to cause the inflowing air currents through said inlet ports to reach and become heated from the exterior of said heating member and to thence escape through the perforations of said side plate, a plurality of burner tubes extending from one 40 end plate to the other below said heating member, a tube supplying mixed air and gaseous fuel in position to be preheated from said burner tubes, and an equalizing 45 receptacle carried by one of said end plates and connecting said supply tube and said burner tubes, into which receptacle preheated air and gaseous fuel is discharged from said supply tube and thence distributed 50 to said burner tubes.

2. A portable heater comprising substantially vertical end plates having upper and lower air inlet ports through their lower portions, a horizontal cylindrical heating member supported at its ends upon and between the upper portions of said end plates above the air inlet ports and provided with a central air heating drum open at both ends, an imperforate substantially horizontal deflector plate located intermediate of the upper and lower air inlet ports between said end plates, and substantially vertical side plates extending from one of said end plates to the other on opposite sides of said heating member and inclosing the space below 55 said heating member to the floor, one of said side plates being perforated, and said several plates being so arranged as to cause the inflowing air currents to enter through said respective air inlet ports to reach and become heated from said heating member and said deflector plate, and to thence escape through the perforations of said side plate.

3. A portable heater comprising substantially vertical end plates having upper and lower air inlet ports through their lower portions, a horizontally cylindrical heating member supported at its ends upon and between the upper portions of said end plates above the air inlet ports and provided with a central air heating drum open at both ends, an imperforate substantially horizontal deflector plate located below said heating member and between said upper and lower air inlet ports and between said end plates, substantially vertical perforated side plates extending from one of said end plates to the other on opposite sides of said heating member and inclosing the space below said heating member to the floor, and a perforated cap member seating upon the upper edges of said end plates and side plates and inclosing the upper portion of said heating member with an intervening air space, said several members being so arranged as to cause the inflowing air currents to enter through said air inlet ports in said side plates and through the lower perforations in said cap member to reach and become heated from the exterior of said heating member, and to thence escape through the perforations of said side plate and upper perforations of said cap member.

In testimony whereof we have affixed our signatures in presence of two witnesses.

EDWARD B. OELKER.
FREEMAN C. LUDLOW.
